(57) **CLAIM**

What is claimed is the ornamental design for a dual-lumen catheter, as shown and described.

DESCRIPTION

FIG. 1 is a perspective view of the dual-lumen catheter showing our new design; and,

FIG. 2 is a front elevation view of the design of FIG. 1. The broken lines are included for the purpose of illustrating environmental structure and form no part of the claimed design.

1 Claim, 1 Drawing Sheet

FIG. 1

FIG. 2
